UNITED STATES PATENT OFFICE.

HENRY W. LARSSON, OF SPRINGFIELD, MASSACHUSETTS, ASSIGNOR TO THE LARSSON WHIP COMPANY, A CORPORATION OF MASSACHUSETTS.

MACHINE FOR DIVIDING RATAN.

SPECIFICATION forming part of Letters Patent No. 694,758, dated March 4, 1902.

Application filed October 26, 1899. Serial No. 734,819. (No model.)

To all whom it may concern:

Be it known that I, HENRY W. LARSSON, a citizen of the United States of America, and a resident of Springfield, in the county of 5 Hampden and State of Massachusetts, have invented certain new and useful Improvements in Machines for Longitudinally and Diagonally Dividing or Stripping Ratan, Wood, &c., of which the following is a full, 10 clear, and exact description.

This invention relates to improvements in machines for splitting or longitudinally dividing strips of ratan or other similar material in such a manner that the two divisions 15 of each of the strips which are run through the machine are endwise tapered and the one constituting the complement of the other.

The invention more particularly relates to a machine for producing from a given cross- 20 sectionally-segmental-shaped strip of ratan which is of substantially uniform width from end to end two divisions thereof, which as to the length of the strip are separated on a line which runs from the side portion at the one 25 end to the opposite side portion at the other end and which splits are produced by being separated on a cutting or dividing plane which is substantially radial to the apex of the stock at all points throughout the length 30 thereof. The divisions produced as aforementioned are especially applicable for employment in making up stocks or bodies of whips.

The invention consists in the combination 35 and arrangement of mechanisms or devices, as hereinafter set forth, and also in the construction of certain of said devices, and all substantially as covered in the claims.

The machine as I have constructed it in an 40 improved and satisfactory form is illustrated in the accompanying drawings, in which—

Figure 1 is a front elevation of the machine. Fig. 2 is a plan view of the same. Fig. 3 is a cross-sectional view vertically as taken on 45 the line 3 3; Fig. 1. Fig. 4 is a view on a somewhat-larger scale of the carrier for the stock-dividing knife and the means for imparting a rotational reciprocatory movement thereto, such parts being indicated as 50 enclosed within a casing suitably constructed therefor. Fig. 5 is a vertical section as taken

on the line 5 5, Fig. 4, guides which are forward and also to the rear of the knife and its carrier being shown as in their appropriate relations to the knife. Fig. 6 is a perspective view of the guide, which is located longitudinally to the rear of the knife. Fig. 7 is a front end view of the guide for the stock, which is longitudinally arranged and rotated forward of the knife. Fig. 8 is a side view 60 of the preferred form of the knife employed in this machine for dividing the longitudinal strips or stock. Fig. 9 is a cross-sectional view on line 9 9, Fig. 8. Fig. 10 is a perspective view of the initial guiding and feeding 65 device for the stock. Fig. 11 is a horizontal sectional and plan view of mechanism located below the bed or table of the machine and actuating the separable mechanism comprised in the feed for the strips at the rear end of 70 the machine. Fig. 12 is a sectional view of parts in detail as taken on the line 12 12, Fig. 11. Fig. 13 is an elevation of the feed-rolls as seen at the front end of the machine looking rearwardly. Fig. 14 is a horizontal sec- 75 tional view of the parts shown in Fig. 5 and as taken about on the line 14 14. Fig. 15 is a side view of a segmental-shaped strip or length of ratan or other material such as this machine is adapted to divide. Fig. 16 is a 80 plan of the strip, showing by dotted line the oblique or inclined line of division. Fig. 17 is a series of cross-sectional views showing at the ends the segmental cross-sectional form of the strip and intermediately cross- 85 sections of the strip divided as taken on the section-line projected from each of these sub-views. Fig. 18 is a plan view showing the strip as half split and the relative location of the knife. 90

Similar characters of reference indicate corresponding parts in all of the views.

In the drawings, A represents the frame or table of the machine, having suitable journals formed on or affixed thereto, the horizontal transversely-arranged main shaft B having the driving-pulley B² thereon. 95

1 represents what I term the "front end" or "forward part" of the machine; 2, the rear end portion thereof; 3, the front side, and 4 100 the rear side, of the machine.

C represents the location of the casing in

which is mounted the annular carrier or holder for the knife *a*.

At *D* is located the initial guide and feed mechanism into which the segments are manually introduced, in line with and to the rear of which is the set of feeding-rolls *E*. Next to the rear of and in line with the said feeding-rolls *E* and which is ahead of and also in line with the knife *a* is the guide *F*. To the rear of the knife in the line of feed of the stock is another guide *G*, while to the rear thereof is the set of feeding-rolls *H*, the upper ones of each pair being separable.

Having in a general way referred to and indicated the location of the various devices or mechanism comprised of important portions in the organization of this machine, a more detailed and definite description of the various devices and mechanisms will be now given.

Referring now to the first set of feed-rolls and the means for imparting thereto their rotational feeding motion in the same direction, it will be seen that the feed-rolls are arranged in upper and lower pairs, six of each being here represented, although the number may be greater or less, as desired. The lower rolls 20 are peripherally V-grooved and have their arbors 22 mounted in stationary bearings. The upper feed-rolls of this set *E* are, as indicated at 23, in the form of circular plinths or comparatively thick disks and have their peripheries adapted to sink but part way into the V-groove peripherally formed in the following feed-wheel. The arbor 24 for each upper feed-roll 23, which is extended toward the rear side of the machine, has its rear end pivotally mounted, as shown at 25 in Fig. 13, whereby the feed-roll 23 may have a rising-and-falling and self-adjusting movement to conform to the top or "back" of the segmental strip to be run therethrough. The mounting for each set of the feeding-rolls has toward the front side of the machine, but located next back of the roll 23, the upstanding duplicated ear-lugs 26, pivoted in which is the elbow-lever 27, the short arm of which is rounded and is in bearing against the top of the arbor or journal-shaft for the roll 23, which runs loose thereon, so that said shaft may have a rising-and-falling motion. The spring 28 is applied on each angle-lever 27 to exert a downwardly-forcing pressure on the roll-carrying shaft 24. The shaft 22 for each lower V-grooved roll 20 has a spur gear-wheel 30 affixed thereon, and the several gears 30 are driven the one from another by intermediate gears 32, while motion is imparted to this train of gearing so that all of the lower rolls are positively driven in the same direction and at the same speed by the gearing interposed between one of the gears 30 and the driving-shaft *B* of the machine, and which will be pointed out as comprising a spur gear-wheel 33 on the shaft 22 for the lower feed-roll, a spur gear-wheel 34 on the main shaft, and an

intermediate gear 35 in mesh with the one 33 and 34. The main shaft has formed on or attached thereto a worm 36, which drives the worm-wheel 37, which is affixed on the axially-vertical shaft 38, rotatable in a suitable journal-bearing therefor, and which has at its upper end above the top of the bed or table *A* of the machine the two scroll-cams *b* and *c*, both rotatable in a horizontal plane and the one lying upon the top of the other.

At the front end of the machine, preceding the series of feed-rolls above described, is the initial feeding device *D* for the segmental strips *x*, which is shown more particularly in Figs. 1, 2, and 10. This device *D* comprises a standard 37, adapted to slide horizontally longitudinally in the way 38 therefor, and this standard is equipped with a portion above its base, which is fitted in the slideway with the upwardly-open longitudinal channel 39, which transversely is of a V shape. Pivoted on the standard 38 is the dog or pawl 40. This is inclined downwardly and rearwardly, its lower end terminating for a pressure-bearing, as exerted by the spring 42 on the strip *x*, and all so arranged that the end of the strip may be forced to the nipping action as exerted by and between the pawl 40 and the adjacent V-grooved part. The strip being once entered between these parts may have only a progressive movement toward the rear end of the machine, for it will be apparent that any tendency to draw the strip in the reverse direction will result in the same becoming clutched. The periodical reciprocatory movement is imparted to the feed device *D* by the thrust-rod 43 in one direction and the spring 44 in the other. The said thrust-rod has its one end pivoted at 45 to the sliding part 37, its other end being forked to receive a guiding engagement with the flanged washer 46, provided at the upper projecting end of the worm-wheel shaft 38. The thrust bar or rod 43 has a depending projection 47, which the scroll-cam *b* engages. Once to every rotation of the shaft 38 the feeder *D* will recede toward the right-hand end of the machine, when suddenly falling off the abrupt part of the cam (indicated at *b*²) it is left subject to the reversing impulse of the spring 44, which drives it forcibly and sharply longitudinally toward the feed-rolls *E*. By placing the end portion of the strip in engagement through the feeder *D* the impulse of the latter will be to project the same forcibly between and to the nipping action of the paired rolls 30 and 32 in the roll-feed mechanism *E*. The strip being carried through the set of feed-rolls *E* enters the V-guide *F*, the same comprising an upright 48, having within its top the channel or groove 49, the base of which is downwardly convergent or of a cross-sectional V contour. The short bar or pressure member 50 is pivotally hung at its forward end, as shown at 52, to upstanding ear-pieces provided on the part 48, the said member 50

having the downward rearward inclination and forced down with a yielding bearing by the spring 53.

The knife *a* is mounted in the knife-holder 5 or knife-carrier *J*, which as a whole is of an annular form, the knife being located within and extending diametrically crosswise of the opening within the knife-carrier. The center of the carrier is exactly or approximately coincident with the common longitudinal horizontal line extending through the apexes of the channel 39 in feeder *D*, the bases of the V-grooves at the tops of the rollers 20 20 of the feed-roll mechanism *E*, and 5 the base of the V-groove 49 in the guide *F*, and the knife which intersects the said axial center of the knife-carrier has its length radial to such center, and the carrier having a capability for rotational movement about said center by means to be hereinafter described causes the knife to assume different radial positions, as it has its traverse bodily across the width of the V-shaped strip or segment being fed past, and to be divided on a slightly oblique line by the knife.

The knife-carrier comprises the annular section 60, having at its inner margin the annular flanges 62 62, projecting beyond the face of the ring-shaped section. The one flange 62 bears peripherally on the circular wall comprised as the boundary of the opening within the casing *C*, the annular clamping-plate 63 constituting the peripheral bearing for the opposite one of said flanges 62. Within in the ring-section 60 is a secondary removable ring section 64, the same having at its rear side the flange 65, which overlaps the edge of the adjacent flange 62 of part 60.

66 represents a clamping-rod having its shank passed through an opening therefor in the ring-section 64 parallel with the axis of such part, such rod having at its forward end the angular engagement member 67 and at its rearwardly-located screw-threaded end receives the clamping-nut 68. As the flange 65 overlaps both the flange 62 of part 60 and the clamping-ring plate 63, the single clamping-rod 66 and its nut holds all of the parts constituting the sectional knife-carrier in place.

The annular part 60 is constructed with a series of gear-teeth 69, meshing with which is the rack 70, which is movable back and forth in a straight line in a guide therefor formed within the casing *C* under the knife-carrier.

The inner ring-section 64 has diametrically opposite posts or lugs 72 72, which have longitudinal alined ways 73, (shown in Figs. 5 and 14,) in which are fitted the movable blocks 74. These blocks have in the inner ends thereof, which are located toward each other, sockets 75 for the reception therein of the trunnions or pivot-constituting members 76 76 of the knife *a*.

Inasmuch as I claim novelty in the cutting blade or knife and a support for the knife on

which the same is pivoted with the cutting edge located back of the pivotal line, I do not wish to be limited to any specific form and manner of mounting of the knife in accordance therewith, but an entirely practical, operative, and satisfactory construction and arrangement is shown in Figs. 3, 4, 5, 8, 9, and 14, in which the blade *a* of the knife has at its ends the integrally-formed bars or members *a*³ *a*³ projected forwardly beyond the cutting edge of the knife. The pivot members or trunnions 76, the common line of which is parallel with the length of the knife, have their common center ahead of the cutting edge *a*⁴.

The aforementioned rack-bar 70, which gives the partial rotary and reciprocatory motion to the knife-carrier, has its rectilinear motions imparted thereto by the engagement 70 with the upstanding cam-roller 77 thereon of the scroll-cam *c*, whereby as the radial widening-cam has its revoluble movement it will force the rack-bar 70 rearwardly, and the spring *c*³ will retract the rack-bar forwardly 75 when the drop or abrupt part of the cam *c*³ has come opposite the said roller. Thus as the strip has its progressive course in a straight line through the machine the knife having the swinging bodily motion will be 80 carried with its forwardly-directed cutting edge against the one convergent side of the strip at or near its forward end, and the knife will by reason of its peculiar motion emerge 85 from the strip at its other end portion and at 90 the opposite convergent side thereof, dividing the strip into two sections, both of which at all points in their lengths are segments, as insured by the knife having its position at all stages of its swing in a line radial to the 95 apex of the segmental strip to be divided and of the guides through which the strip is fed 100 or conducted.

The mounting of the knife for the secondary oscillatory movement is found to be a 105 matter of great importance in the practical working of this machine, especially where it is to be employed for producing duplicated endwise-tapered cross-sectionally-segment-shaped divisions from one of the segments *x* 115 of ratan, for the reason that the cutting edge of the knife will most readily make its initial incision or take into the strip *x* at the one side, and after having entered and while the cutting or dividing action is progressing the 120 knife may conform to inequalities of the grain and prevent the edge of the knife from thereby becoming turned or broken, and yet in practice the splitting-line diagonally of the strip which is maintained is singularly 125 straight, continuous, and clean, no perceptible undulations at the surfaces following or opened up by the division as effected by the knife being found.

Protracted use of the dividing mechanism 130 described has been had, and notwithstanding the fact that the knife *a*, constructed and

mounted as shown, was made of inferior and comparatively soft steel and used when in a comparatively dull condition the splits or sub-sections x^2 were brought forth out of the machine with the sharpest and cleanest surfaces imaginable, even at their extremities, where the thickness was no greater than a thin shaving and where the stock was most flexible.

- On some classes of work where the greatest accuracy of the division is not necessarily so great as in making splits or tapered segmental sections for whips the knife may be employed by being mounted on the holder, which gives it its traverse relatively to the strips to be divided on an oblique line without necessarily being pivotally mounted on or in the holder for the secondary self-conforming oscillatory motion which has been described; but hence I do not confine myself absolutely to the employment of the knife which is pivotally mounted on the holder, for under certain circumstances I have acquired successful results when the knife was non-pivotally mounted.
- The guide G, which likewise is of the V shape in cross-section, has its position and arrangement longitudinally to the rear of the knife, and a detail view of this appliance is given in Fig. 6. This guide advantageously is constructed with the extension 80, which is projected through the knife-carrier back of the knife and is secured on and supported by the upright 48, in the top of which is comprised the V-guide, heretofore designated by F.
- This device G is provided for the purpose of keeping the split halves of the strip x together and for insuring the conducting thereof with certainty to and between the rolls comprised in the feeding device H, which is for carrying the strips out of the machine and insuring positively the continued longitudinal movement thereof, especially at the latter part of the operation, at which the end portion of the strip last approaching the knife and after it has passed the series of feed-rolls E will even then be carried to and past the knife. These rolls are substantially duplicates of the rolls 20 and 23 hereinbefore mentioned, the lower ones being V-grooved and running in fixed bearings, while the upper disk rolls 23^a, mounted for yielding movements upwardly against the pressure of the springs 28^a in the same manner as are the corresponding disk rolls 23 of the set E, have means combined therewith for positively periodically elevating them in time to permit the entrance between them and the V-rolls therebelow of the forward now-divided end of the strip x .
- The means for imparting the separating movements of the upper disk rolls will be now described.

An upstanding vertically-movable rod or bar 82 carries at its upper end a cross-bar 83, which engages onto the collars provided at the outer or front ends of the bars 24^a, on which

the disk rollers are journaled. The vertical rod 82 has on its lower end the cam face or incline 84, adjacent which is located the extremity of a lever 85, which is pivotally mounted at 86 and arranged to swing in a horizontal plane under the bed or table of the machine. The extremity of the said lever 85, adjacent the part 84, is beveled or inclined, as indicated at 87, to work easily for a crowding action against the cam-incline 84. A projection 88, upstanding above the top face of the worm-wheel 37, once in every revolution of said worm-wheel, which corresponds to each complete operation of the machine, swings the lever 85 into the position indicated by the dotted lines in Fig. 11, and thereby insures at the proper instant the separation of the upper disk rolls 23^a.

Having thus described my invention, what I claim, and desire to secure by Letters Patent, is—

1. The combination with a guide for the strip or stock, of a cutter, a holder by which the cutter is supported, and means for moving the holder whereby the cutter is given a gradual swinging motion transversely relatively to the line of movement of the stock on an axis parallel thereto.

2. The combination with means to longitudinally guide the stock or strip, of a knife located adjacent the line of movement of the strip, a movable holder by which the knife is supported, and means for moving the said holder whereby the cutting plane of the knife is gradually changed transversely relatively to the length of the strip on an axis parallel thereto.

3. The combination with means to longitudinally guide the stock or strip, and means for imparting a longitudinal feed movement of the strip, of a knife located adjacent the line of the strip, a movable holder by which the knife is supported, and means for moving the said holder whereby the cutting plane of the knife is gradually changed transversely relatively to the line of feed of the strip on an axis parallel thereto.

4. The combination with means for longitudinally guiding the strip or stock, and means for imparting a feed motion to the strip, of a knife, a holder adapted for a rotational movement by which the knife is supported adjacent the line of feed movement of the strip and behind the knife, means for rotationally moving the said holder whereby the knife is caused to assume successively positions transversely relatively to the length of the strip, and a second feeding means provided behind the location of the knife, substantially as described.

5. The combination with means for longitudinally guiding the strip or stock, and means for imparting a feed motion to the strip, of a cutting-knife, a carrier adapted for a rotational movement by which the knife is supported adjacent the line of the strip and means

for rotationally moving the said carrier whereby the knife is caused to pass through changing planes transversely of the length of the strip, and a second feeding means located in the line of feed of, and beyond the knife, which comprises members one of which is separable from the other, and means for causing the opening of the one member from the other to permit the entrance therebetween of the end portion of the strip which has passed subject to the action of the knife.

6. The combination with a feeding means for the strip or stock, and a guide back of, or beyond it, of a knife and a carrier adapted for a rotational movement by which the knife is supported located beyond or back of the said guide, means for moving the knife-carrier whereby the knife is given a gradual rotational swinging motion transversely relatively to the line of feed movement of the stock, a second guide in the line of feed beyond the knife, and a second feeding means beyond the last-named guide to which the latter guides the split portion of the stock.

25 7. The combination with means to longitudinally guide the stock or strip, of a knife located adjacent the line of feed of the strip, a movable holder or carrier for the knife by which it is pivotally supported with its cutting edge behind the pivotal center of its mounting upon the carrier, and means for moving the said carrier whereby the length of the knife is gradually moved transversely to the line of feed of the strip.

35 8. The combination with a V-shaped guide, of a knife located adjacent the line of and to the rear of the guide, a holder supporting the knife pivotally and which holder is mounted for an arc movement, the center of the movement of the holder and the knife being substantially coincident with the apex of the guide, and means for imparting the reciprocatory arc movement to the holder on an axis parallel with the line of feed movement of the stock.

45 9. The combination with a guide having convergent sides, of the knife-carrier and knife pivotally supported by the carrier, the carrier being mounted to move in an arc having an axis parallel with the line of feed of the stock and arranged to present and maintain the knife with its length always in a line radial to the intersection of the angular sides of the guide.

55 10. The combination with a guide having opposite convergent sides, of a knife in line with the guide, a holder by which the knife is pivotally supported thereon and mounted for an arc movement, the line of pivotal support of the knife on the holder being ahead of the cutting edge of the knife, and means for imparting a rotational reciprocatory movement to the holder in its said arc course.

65 11. A guide for conducting the stock longitudinally, having convergent sides, and means for feeding the stock through the guide, a

knife located adjacent the line of feed of the stock with its length radial to the apex of the convergent sides of the guide, and as regards said guide and knife, means for causing a movement of the one relatively to the other whereby the radial relations of the cutting edge of the knife to the convergent guide are varied for the purpose set forth.

12. A means for supporting the segmental stock, a knife located adjacent the longitudinal line of the stock with its length radial to the apex thereof, and as regards said stock-support and knife, means for causing a movement of the one relatively to the other whereby the radial relations of the cutting edge of the knife to the segmental strip are varied for the purpose set forth.

13. The combination with a guide for the stock to be divided, of an annular knife-carrier mounted for a rotatable movement, a knife mounted within and across the opening in said knife-carrier, and means for imparting a rotational motion to said carrier, for the purpose set forth.

14. The combination with a casing having a circular opening therein, an annular knife-carrier rotatably mounted within the casing, and means for imparting its rotational movements thereto, a knife mounted within and across the opening in the casing and a V-shaped guide for directing a segmental strip to be divided through the annular knife-carrier and subject to the action of the knife-carrier thereby.

15. The combination with an annular knife-carrier, provided with gear-teeth, a suitably hollow part in which said carrier is mounted for a rotational motion, a knife supported by and across the opening in said carrier, a rack-bar meshing in said gear-teeth, and a cam operating the rack-bar in one direction and a retracting-spring therefor.

16. The combination with a V-guide for the stock to be divided, of an annular knife-carrier mounted for a rotational motion beyond the guide, a knife pivotally mounted within said angular carrier having the length of its cutting edge extending crosswise of the opening within said carrier and means for imparting a rotational motion of the carrier to result in a bodily-swinging motion to the knife.

17. The combination with a V-shaped guide, of a knife in line with and beyond the guide, a holder in which the knife is pivotally supported, and mounted for a rotational movement in an arc course, the center of which movement is coincident with the apex of the V-guide, means for imparting the motion to the carrier, a second V-guide arranged in line with the first one back of the knife, a feed mechanism ahead of the first guide and a feed mechanism to the rear of the second guide, for the purposes set forth.

18. The combination with a cross-sectional V-shaped guide for the segmental-shaped stock to be divided, of an annular knife-car-

rier mounted for a rotatable movement having its center coincident with the apex of the guide, a knife mounted within and across the opening in said knife-carrier radially relatively to said apex, and means for imparting rotational motion to said carrier, for the purpose set forth.

19. The combination with a casing having a circular opening therein, an annular knife-carrier rotatably mounted within the casing, and means for imparting its rotational movements thereto, a knife mounted within and across the opening in the casing and in a line which is radial to or intersects the center of the carrier, and a V-shaped guide for directing a segmental strip to be divided through the annular knife-carrier and subject to the action of the knife-carrier thereby, which guide has its apex coincident with the center of the annular knife-carrier.

20. The combination with an annular knife-carrier, provided with gear-teeth, a suitably-hollow part in which said carrier is mounted for a rotational motion, a knife pivotally supported by, and centrally across the opening in, said carrier, a rack-bar meshing in said gear-teeth, and a cam operating the rack-bar in one direction and a retracting-spring therefor.

21. The combination with a knife movably mounted and means for imparting a swinging motion thereto, substantially as described, of a V-guide in advance of the knife, a series of feed-rollers in advance of the guide, and a feeding device in advance of the rollers, the same comprising longitudinally-sliding part having a V-channeled portion, and a spring-pressed pawl 40 arranged inclined to the length of the channeled portion, the thrust-rod 43 the cam b, and means for rotating it and the retracting-spring 44, substantially as described.

22. In a machine of the character described, the combination with the knife and the annular carrier in which it is mounted provided with gear-teeth, and the rack-bar 70, and the initial guiding device D comprising the longitudinally-sliding member 37 having the channeled portion, and a spring-pressed gripping-pawl 40, of the shaft 38 having thereon the scroll-cams b and c, the latter co-operating with the rack-bar, and a thrust-rod connected to the sliding part 37 with which the cam b co-operates, retracting means for the rack-bar and said slide, and a series of feeding-rolls between the said initial feeding device and the knife, and means for rotating them, substantially as described.

23. The combination with the annular knife-carrier and the knife mounted therewithin, and supported thereby, together with means for turning the carrier, of a V-shaped guide located in advance of, and with the longitudinal line thereof which is coincident with its apex, in the center of the carrier, and the pressure member 50, substantially as described.

24. The combination with the annular knife-

carrier, having the knife mounted centrally crosswise thereof, and therewithin, and means for turning said carrier around a fixed center, of a V-shaped guide located in advance of, and in line with, the center of the carrier, substantially as described, and having applied therein the pawl or bar 50 which is pivoted at its forward end and inclined rearwardly, and the pressure-spring 53, substantially as described.

25. In a machine of the character described, the annular knife-carrier having the knife mounted therewithin, of the V-guide in the line of the center of the carrier, and a second V-guide longitudinally extending and located to the rear of the knife and having a portion extended through the opening in the carrier to one side of the knife, and confined on and supported by the first V-guide, substantially as shown.

26. In a machine of the character described, the combination with the casing C having a circular opening therewithin, and the ring-section 60 rotatably mounted within the casing and supported for its movements thereby, the secondary annular section removably secured in the ring-section 60, and having the opposite inwardly-projecting members 72, 72, having the aligned ways 73 therein, the blocks 74 removable in said ways and having the sockets 75, 75, and the knife a having the end studs or pivot members 76, 76, engaged in said sockets, and means for imparting rotational movements to the carrier, substantially as described.

27. In a machine of the character described, which comprises the knife, and means for feeding the stock thereto, and the feeding-out rollers, comprising lower rollers having fixed bearings and upper rollers which are separable from the lower rollers, the combination with the separable upper rollers of a vertical rod 82 having the cross-bar 83, and provided at its lower end with the inclined cam 84, the intermediately-pivoted lever 85 having an inclined portion thereof co-operating with said part 84, a rotary wheel having the projection 88 adjacent which the extremity of said lever 85 is extended, and means for rotating said wheel.

28. In a machine for dividing cross-sectionally V-shaped strips of ratan or like material from end to end on a line inclined to the common median of the strip, the combination with a V-shaped guide for the strip, a cutter therebeyond, a holder by which the cutter is supported and means for moving the holder whereby the cutter is given a gradual swinging motion across the width of the opening in said V-shaped guide.

29. In a machine of the character described the combination with the guide having a V-shaped channel therein of a bar 75 movably mounted in the channel and a spring exerting a pressure against the bar to force it toward the base of said channel.

30. In a machine of the character described, the combination with part F having the V-shaped guide-channel of the pressure-bar 75 pivoted at its one end, and the spring 53 bearing against the bar.

31. The combination with the feed-rolls E having peripheral V-grooves, 20 of the set of coacting, yielding rolls 23 narrower than said

grooves, and pressure-springs for the latter rolls. ¹⁰

Signed by me at Springfield, Massachusetts, this 24th day of October, 1899.

HENRY W. LARSSON.
